SCANNING-WAVE GENERATOR SYNCHRO-
NIZING SYSTEMJohn C. Wilson, Bayside, N. Y., assignor to
Hazelton Corporation, a corporation of Dela-
ware

Application August 26, 1938, Serial No. 226,872

9 Claims. (Cl. 178—69.5)

This invention relates to television systems and more particularly to the synchronization of scanning-wave generators embodied in such systems.

In television systems of the scanning beam type, in order to effect scanning of the target of the reproducing device by the beam, saw-tooth current or voltage waves are generated and utilized to produce, respectively, electromagnetic or electrostatic fields of saw-tooth wave forms which 5 deflect the beam in two directions normal to each other for line and field scanning, thereby to trace the well-known rectilinear scanning pattern upon the target of the tube. Synchronizing pulses are generally utilized to control the operation of 10 the scanning-wave generators, thereby to synchronize the scanning action with other related actions in the system. For example, synchronizing pulses are usually transmitted as modulation components impressed upon the same television carrier wave as the video-frequency components and these pulses are detected and utilized at the receiver to synchronize its scanning action with the corresponding scanning at the transmitter.

25 It is important that the synchronization be accomplished with precision in order that proper scanning may be obtained. This is especially true in scanning systems of the interlaced type, where the field-scanning frequency is not an integral submultiple of the line-scanning frequency so that the lines of one field interlace or fall between the lines of a preceding field and a plurality of successive fields thus constitute a single frame or a single complete image. To obtain a precisely interlaced relation between the successive fields, it is especially important that the field trace scansions be initiated at precisely related intervals.

Heretofore it has been the practice to synchronize scanning-wave generators at the termination of each trace-scanning period or, in other words, at the initiation of each retrace period. This has been accomplished by applying synchronizing pulses to the scanning generators so as to trigger their operation at these points. However, it has been found that, with such synchronization, it is still difficult to initiate the trace-scanning actions at precisely the required points in the scanning cycles.

50 It is an object of the present invention, therefore, to provide an improved television scanning system embodying scanning-wave generating means and synchronizing means whereby there may be developed scanning waves having their

trace periods initiated at precisely predetermined times.

In accordance with the present invention there is provided a television system adapted for the translation of a signal including scanning synchronizing components which occur during predetermined recurring scanning intervals. The system comprises a generator for developing scanning waves having trace and retrace periods. There are provided also means responsive 5 to the synchronizing components in the signal translated by the system for developing synchronizing impulses. Means are further provided for utilizing these impulses to synchronize the generator at the initiation of each trace-scanning 10 period.

In a preferred embodiment of the invention, the system is adapted for the translation of a signal which includes synchronizing pulses which have leading edges occurring during the recurring scanning intervals and includes means responsive to such leading edges of the synchronizing pulses in the signal input to the system for developing synchronizing impulses representing the initiation of each retrace-scanning period as well as additional synchronizing impulses delayed for predetermined periods with respect 20 to the main synchronizing impulses and representing initiation of each trace-scanning period. These impulses are utilized to synchronize the 25 generator at the initiations of both the trace- and retrace-scanning periods.

In the specification and appended claims, the term "pulse" is employed in accordance with its conventional meaning to describe an amplitude variation in a signal which includes a departure from a given value and subsequent return to such value, after a greater or lesser period. The term "impulse" is employed to indicate a single amplitude variation in a signal. For example, in a signal of rectangular wave form, each rectangular pulse comprises a leading edge constituting one impulse and a trailing edge constituting a second separate impulse. Either of these impulses may, of course, represent information or be utilized to effect a controlling action separately, if desired.

For a better understanding of the present invention, together with other and further objects thereof, reference is had to the following description taken in connection with the accompanying drawing, and its scope will be pointed out in the appended claims.

In the accompanying drawing, Fig. 1 is a circuit diagram, partially schematic, of a complete

television receiving system including scanning-wave generating and synchronizing apparatus embodying the present invention, while Fig. 2 is a group of curves illustrating the forms of the signal waves utilized and developed in accordance with the present invention, to aid in the understanding thereof.

Referring now more particularly to Fig. 1 of the drawing, there is illustrated a television receiving system which may be of either the tuned radio-frequency or superheterodyne type and including, in cascade, an antenna system 10-11, a carrier-frequency translator 12, a detector 13, a video-frequency amplifier 14, and an image-reproducing device 15, such as a cathode-ray reproducing tube. Where the receiver is of the superheterodyne type, the conventional frequency changer and intermediate-frequency amplifier are included in the carrier-frequency translator 12. A line-frequency scanning-wave generator 16 and a field-frequency scanning-wave generator 17 are coupled to the video-frequency amplifier 14 by way of a suitable synchronizing signal separator 18 and are connected to the scanning elements of the device 15 in a conventional manner. The generator 17 includes synchronizing means constructed in accordance with the present invention. This generator is shown in detail and will be hereinafter further described. The parts of the system indicated in block form may be of any conventional construction and operation.

Since the operation of the system of Fig. 1, as thus far described, is, in general, well understood in the art, a detailed explanation of its operation is deemed unnecessary. Briefly, however, vision-modulated carrier waves are intercepted by the antenna 10-11 and selectively amplified in the carrier-frequency translator 12. Where the receiver is of the superheterodyne type, the signals are impressed on a frequency changer in the translator 12 where they are converted into an intermediate-frequency signal and thereupon further selectively amplified. The amplified signal from the translator 12 is delivered to the detector 13, in which there are derived the modulation-frequency components including the video-frequency and synchronizing components. The modulation-frequency components are supplied to the video-frequency amplifier 14, wherein they are amplified and supplied in the usual manner to a brilliancy control element of the device 15. The modulation-frequency components are also supplied to the synchronizing signal separator 18, wherein the line-synchronizing and field-synchronizing components are separated from the video-frequency components and from each other and applied to the scanning-wave generators 16 and 17, respectively.

The intensity of the scanning beam of the device 15 is thus modulated or controlled in accordance with the video-frequency voltages impressed on its control element in the usual manner. Saw-tooth scanning waves developed by the generators 16 and 17 are controlled by the synchronizing components supplied from the separator 18, as will be hereinafter further described, and are utilized in the conventional manner to produce electric fields of saw-tooth wave form to deflect the scanning beam in two directions normal to each other so as to trace the usual scanning pattern upon the screen of the device, thereby to reconstruct the transmitted picture.

Referring now more particularly to the portion of the system of Fig. 1 embodying the pres-

ent invention, the generator 17 comprises two component parts including a driven scanning-wave generator indicated generally at 19 and a relaxation oscillator indicated generally at 20. The generator 19 comprises energy-storage means such as a condenser 21. Condenser 21 is provided with a charging circuit including a source of direct current, indicated at +B, and an impedance device, preferably a constant current device in the form of a pentode tube 22, as shown. For the purpose of adjusting the rate of flow of charging current through the tube 22, thereby to control the amplitude of the wave developed by the generator, there is provided a source of adjustable grid-bias voltage, for example, a battery 23 with a voltage-divider resistor 24 connected thereacross and having an adjustable tap. The condenser 21 is also provided with a discharging circuit comprising the space current path of a vacuum tube 25 connected thereacross and normally biased beyond cutoff. A constant current thus flows through the tube 22 to charge the condenser 21 linearly over a relatively long period. The tube 25 serves periodically to discharge the condenser 21, thereby to develop thereacross a scanning voltage wave of saw-tooth wave form.

The relaxation oscillator 20 comprises a vacuum tube 26, the anode circuit of which includes an inductance element 27 connected in series with a source of operating potential, indicated at +B. The control grid-cathode circuit of the tube 26 includes an inductance element 28 coupled to the inductance element 27 and connected to a source of grid-biasing potential indicated at -C. An adjustable resistor 29 is included in the cathode circuit of the tube 26 for adjusting the bias on the tube, thereby to determine the periodicity of the oscillator. The anode of the tube 26 is coupled to the control grid of the tube 25 by way of a coupling condenser 30 and leak resistor 31. For the purpose of applying field-frequency synchronizing pulses to the oscillator 20, an output circuit of the separator 18 includes an inductance element 32 which is inductively coupled to the inductance element 28, as shown.

Considering the operation of the oscillator 20, at the beginning of each cycle current flows from the source +B through the inductance element 27, the tube 26 and resistor 29 gradually rising in value approximately linearly. The change in the current in the inductance element 27 induces a voltage in the inductance element 28 of such polarity as to increase the potential of the grid of the tube 26 positively, increasing the conductance of the tube during this part of the cycle to a maximum value. When, however, the rate of change of current through the element 27 decreases, the voltage induced in the element 28 and, hence, the voltage on the grid of the tube 26 also decreases. This continues until the resultant grid voltage and, hence, the conductance of the tube 26 are decreased to such values that the rate of change of anode current reverses, that is, the current begins to decrease. This point represents the end of the trace period. The induced voltage, therefore, reverses and the grid potential becomes more negative, effecting a regenerative action rapidly cutting off the anode current and rendering the tube 26 inoperative. The grid potential thereafter assumes its initial value, so that current again begins to flow through the tube and the cycle begins de novo. The current through the inductance element 27 is thus of saw-tooth wave form while the voltage

across the element 21, being the differential of the current, is of recurring-pulse wave form.

The general operation of the system may best be explained with reference to the time-amplitude curves of Fig. 2. Curve A illustrates the wave form of the field-synchronizing signal delivered from the separator 18 and impressed upon the grid of the tube 26 by way of the inductances 32, 28. The synchronizing pulses *f* occur at the field-scanning frequency, their leading edges, indicated by the arrows, constituting impulses which are precisely timed to correspond to the initiation of successive field-scanning retrace periods, in accordance with the usual practice. Their durations, however, due to various actions and characteristics of the system, are ordinarily not uniform at the point in the system where they are utilized.

The synchronizing pulses *f* are applied positively to the control grid of the tube 26 so that their leading edges initiate its firing. The oscillator 20 thus develops across the inductance element 27 very large voltage pulses, the amplitudes and durations of which are substantially independent of the synchronizing signal, as indicated by curve B. Where the invention is employed in connection with certain types of scanning-wave generators it may be desirable to limit the amplitude of the constant deviation control pulses. This, of course, may be readily accomplished by suitably designing the constant-duration pulse oscillator in accordance with well-known practice. Each of the pulses *p* of the signal developed by the oscillator 20 thus includes a first impulse, that is, a leading edge, and a second impulse, that is, a trailing edge. The duration of these pulses is independent of the synchronizing signal and of a precise predetermined value *a* dependent only upon the circuit constants of the oscillator; thus, the first impulses are made to occur at the initiations of the retrace-scanning periods and the second impulses determine the initiations of the trace-scanning periods. In other words, the pulses have a duration substantially equal to the retrace-scanning periods and the oscillator 20 may be said to constitute a time-delay synchronizing means, since the trailing edge impulses of the constant-duration pulse are delayed for predetermined periods with respect to the leading edges of the synchronizing pulses in the signal translated by the system.

The signal thus developed by the oscillator 20 is applied positively to the control grid of the tube 25 of generator 19 and is effective to render the impedance of this tube extremely low for a period long enough substantially completely to discharge the condenser 21 and to maintain the tube 25 conductive for an interval thereafter. The voltage developed across the condenser 21, therefore, is of a wave form such as is illustrated by curve C of Fig. 2, the trace portions indicated at *t* corresponding to the periods during which the condenser 21 is charged linearly and the retrace portions *r* corresponding to the periods when the pulses *p* from the oscillator 20 are applied to the tube 25 so that the condenser 21 is discharged. Each trace portion *t* is initiated precisely at the trailing edge of a pulse *p* when the discharge tube 25 is suddenly biased beyond cutoff. It will be seen, therefore, that not only is the generator 19 synchronized at the initiation of the retrace period *S*₁ by the leading edges or first impulses of the pulses supplied from the oscillator 20, but also the trailing edges *S*₂ of these pulses provide a synchronizing impulse which synchronizes the

operation of the generator 19 to initiate each trace-scanning period. Moreover, since the trace synchronizing impulses are precisely timed, due to the independence of operation of the oscillator 20, the trace-scanning periods of the generator 19 are initiated with precision, so that an exact interlaced relationship between successive scanning fields is obtained.

It will be appreciated that the apparatus which has been described and illustrated comprises only one arrangement for practising the present invention and that the essential principles of the present invention, including the synchronizing of an oscillator at the initiation of each trace-scanning period and each retrace-scanning period and the provision of individual synchronizing impulses for accomplishing each of these actions, may be obtained with various other arrangements. Moreover, while the preferred embodiment of the invention which has been illustrated and described in detail comprises a system in which a scanning wave is developed which includes a quiescent period between the termination of the discharge or retrace portion of the scanning wave and the initiation of the trace portion thereof, it will be appreciated that the present invention is readily adaptable for use in connection with a system wherein a scanning wave is developed in which the trace periods initiate immediately upon termination of the discharge or retrace portions of the scanning wave. The system described, however, is deemed preferable to the last-mentioned system in that the trace periods always initiate from a reference level, whereas this is not necessarily true in the case of the wave which does not include the quiescent period.

While there has been described what is at present considered to be a preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A television system adapted for the translation of a signal including synchronizing components occurring during predetermined recurring scanning intervals, comprising a generator for developing scanning waves having trace and retrace periods, means responsive to said components in the signal translated by the system for developing synchronizing impulses, and means for utilizing said impulses to synchronize said generator at the initiation of each trace-scanning period.

2. A television system adapted for the translation of a signal including synchronizing pulses having leading edges occurring during predetermined recurring scanning intervals, comprising a generator for developing scanning waves having trace and retrace periods, and time-delay synchronizing means responsive to said leading edges of said pulses in the signal translated by the system for synchronizing said generator at the initiation of each trace-scanning period.

3. A television system adapted for the translation of a signal including synchronizing pulses having leading edges occurring during predetermined recurring scanning intervals, comprising a generator for developing scanning waves having trace and retrace periods, means responsive to said leading edges of said pulses in the signal

translated by the system for developing impulses delayed for predetermined periods with respect thereto, and means for utilizing said impulses to synchronize said generator at the initiation of 5 each trace-scanning period.

4. A television system adapted for the translation of a signal including synchronizing pulses having leading edges occurring during predetermined recurring scanning intervals comprising a 10 generator for developing scanning waves having trace and retrace periods, means responsive to said leading edges of said pulses in the signal translated by the system for developing pulses of predetermined durations, and means for utilizing 15 the trailing edges of said last-mentioned pulses for synchronizing said generator at the initiation of each trace-scanning period.

5. A television system adapted for the translation of a signal including synchronizing pulses 20 having leading edges occurring during predetermined recurring scanning intervals, comprising a generator for developing scanning waves having trace and retrace periods, a constant-duration pulse generator, means for utilizing said leading 25 edges of said pulses in said signal translated by the system for synchronizing said constant-duration generator at the initiation of each constant-duration pulse, and means for applying 30 said constant-duration pulses to said scanning-wave generator to synchronize its operation at the initiation of each trace-scanning period.

6. A television system adapted for the translation of a signal including synchronizing components occurring during predetermined recurring scanning intervals, comprising a generator 35 for developing saw-tooth scanning waves having trace and retrace periods, a generator for developing constant-duration voltage pulses of predetermined durations substantially equal to the retrace-scanning periods, means for utilizing said synchronizing components in the signal translated by the system to synchronize said constant-duration generator, and means for utilizing the trailing edges of said constant-duration pulses to synchronize said scanning-wave generator at the initiation of each trace-scanning period.

7. A television system adapted for the translation of a signal including synchronizing components occurring during predetermined recurring scanning intervals, comprising a genera-

tor for developing scanning waves having trace and retrace periods, means responsive to said components in the signal translated by the system for developing synchronizing impulses corresponding to the initiations of trace- and 5 retracing periods during said scanning intervals, and means for utilizing said impulses to synchronize said generator at the initiation of each trace-scanning period and each retracing period. 10

8. A television system adapted for the translation of a signal including synchronizing components occurring during predetermined recurring scanning intervals, comprising a scanning generator including capacitance means, charging 15 and discharging circuits for said capacitance means, and control means for effecting periodic charge and discharge of said capacitance means to develop a saw-tooth scanning wave including trace- and retrace-scanning periods, means for 20 deriving from said synchronizing components in the signal translated by the system pulses having durations corresponding to the durations of the retracing periods, and means for applying 25 said last-mentioned pulses to said control means to synchronize the operation of said generator, thereby precisely to determine the initiation of each of said retracing and trace-scanning periods.

9. A television system adapted for the translation of a signal including synchronizing components occurring during predetermined recurring scanning intervals, comprising a scanning generator including capacitance means, charging and discharging circuits for said capacitance means, a vacuum tube for controlling said circuits, said tube being normally nonconductive to effect charging of said capacitance means and being periodically rendered conductive to effect discharge of said capacitance means, thereby to develop across said capacitance means a saw-tooth scanning wave including trace and retrace 40 periods, means for deriving from said synchronizing components in the signal translated by the system pulses having durations corresponding to the durations of the retracing periods, and means for applying said last-mentioned pulses positively to said vacuum tube to render 45 said tube conductive only during said retracing periods.

JOHN C. WILSON.
